Primary Examiner — Mitchell Siegel(74) Attorney, Agent, or Firm — Bejin Bieneman PLC(57) CLAIM

The ornamental design for golf club headcover, as shown and described.

DESCRIPTION

FIG. 1 is a perspective view of a golf club headcover including a body, in the shape of a hockey glove, and a sleeve extending from the body for receiving a head of a golf club; FIG. 2 is another perspective view of the golf club headcover; FIG. 3 is a right side view of the golf club headcover; FIG. 4 is a left side view of the golf club headcover; FIG. 5 is a rear view of the golf club headcover; FIG. 6 is a front view of the golf club headcover; FIG. 7 is a top view of the golf club headcover; and, FIG. 8 is a bottom view of the golf club headcover. The broken line showing is included for the purpose of illustrating and forms no part of the claimed design.

1 Claim, 7 Drawing Sheets(56)
